UNITED STATES PATENT OFFICE

JAMES H. SHERTS, OF GLEN RIDGE, NEW JERSEY, ASSIGNOR TO DU PONT VISCOLOID COMPANY, OF WILMINGTON, DELAWARE, A CORPORATION OF DELAWARE

HEATING APPARATUS

Application filed October 27, 1928. Serial No. 315,440.

This invention relates to heating apparatus and has particularly to do with apparatus wherein articles, such as safety glass "sandwiches", may be subjected to heat and pressure. While not restricted to use in the manufacture of safety glass, the invention is described with more particular relation to that industry.

In the manufacture of safety glass a sandwich is assembled comprising two sheets of glass with a sheet of strengthening material, such, for example, as a sheet of cellulose ester plastic, therebetween, and this sandwich is subjected to heat and pressure in order to firmly unite the elements of the sandwich into a unitary article. The present apparatus is of a type which enables it to desirably serve for the uniting of the elements of safety glass sandwiches.

One object of the invention is to provide an apparatus by which articles may be subjected to heat and pressure. A further object is to provide an apparatus whereby safety glass sandwiches may be subjected to heat and pressure, applied by a suitable fluid medium, to unite the elements of the sandwich. To these ends and also to improve generally upon apparatus of the character indicated, the invention consists in the various matters hereinafter described and claimed.

In the accompanying drawings, in which the figures are of somewhat elementary character, Figure 1 is a top plan view of the container for the sandwiches and the fluid used for applying heat and pressure to the sandwiches, with the cover of the container removed; Figure 2 is an elevational view of the container shown in Figure 1; Figure 3 is a side view taken substantially in the direction of the arrow 3 in Figure 1 with the side of the container broken out; Figure 4 is an elevational view, partially broken out to economize space, of a bag for containing a sandwich when the sandwich is treated in the container; and Figure 5 is an elevational view of the upper end of a bag such as that shown in Figure 4, showing the mechanism whereby the bag is closed and opened at its sandwich-receiving end.

Referring now to the drawings, the illustrated apparatus comprises in general a container 1 of any suitable material, say steel, having the removable closing top 2. The container 1 is for the reception of bags, as 3, for holding each a safety glass sandwich 4 to be treated. The illustrated container 1 is divided into separated chambers, as quadrants 5, 5a, 5b, and 5c, by partitions 6, 6a, 6b, and 6c extending from the bottom of the container and abutting the cover 2. Each of the quadrants is divided by any suitable number of partitions, as 8a, 8b, and 8c, into a series of compartments each for holding any desired number of bags 3. The various partitions are attached to, and extend between, the outer wall X and central cylindrical wall Y of the container. Each quadrant is provided with a liquid supply pipe 9, valved at 9a, adjacent its bottom, and a liquid discharge pipe 10 adjacent its bottom. The partitions 8a, etc., alternately extend from the bottom of the container to short of the cover 2 and from short of the bottom 11 of the container to a point in contact with the cover, as shown at 12 and 13 in Figure 3. The bags 3 are suitably attached to the cover, as by hooks 14 and 15, on the bag and the cover respectively, thus suspending the bags in the compartments of the container. To permit escape of air from the container when filling, a vent pipe 7, valved at 7a, is provided and connected, as at 7b, with each quadrant.

The apparatus may be used as follows. With the cover 2 removed from the container a desired number of bags 3 (e. g. a sufficient number to fill all compartments), each containing a safety glass sandwich, is suspended from the cover, a vacuum being desirably placed on each bag, the air exhausted from the bag, and the bag sealed under vacuum, prior to the bag being sealed in the container, as next explained. The cover is now placed upon the container, thus suspending the bags with their contained sandwiches in the compartments of the container, it being understood that the bags are so located on the cover that they will mate with the various compartments. The cover having been closed liquid-

tight upon the body of the container, water is now introduced into the quadrants to fill the same, the control valve 10a in the outlet 10 being closed, and the valve 7a open; and 5 after filling, the valve 7a is closed. The water is now heated to any desired temperature and flowed through the container under any desired pressure and in such volume as to keep the container full. (Conveniently this 10 may be carried out by connection of the pipes 9 and 10 to a suitable heater and pressure pump, as will be understood by those skilled in the art, the water flowing in at the pipe 9 and out at the pipe 10 and being returned 15 to the pipe 9 through the heater and pressure pump.) The water passes through each quadrant and up and down over the partitions, as indicated by the arrows in Figure 3. The temperature and pressure will, of course, 20 vary with circumstances, but, as a general rule for safety glass of the type above indicated, a pressure of 150 pounds per sq. in. upward and a temperature of, say, 250° F. are desirable. When the temperature and 25 pressure have been sufficiently applied, say for 20 minutes, as will be understood by those familiar with the art of making safety glass, the water may be drawn out of the container, the cover lifted, and the sandwiches, with 30 their elements now united, removed from the bags.

It will be noted that the described container and associated bags provide an apparatus which can be quickly loaded with a 35 large number of sandwiches, so that not only may such a number of sandwiches be treated at one time, but also this number of sandwiches may be quickly loaded into, and removed from, the receiver. Desirably three 40 covers for a receiver may be provided, so that one may be in the process of attaching the bags thereto, another will be in use upon the receiver while the sandwiches attached thereto are under treatment, and yet another will 45 be in the process of having the bags removed therefrom.

While there is shown a container divided into four separated compartments, as 5 and so forth, it will be understood that the receiver may be divided into any desired number. Also, while the compartments 5, and so forth, are shown as each provided with three baffles 8, etc., it will be understood that 50 as many baffles as desired may be used.

Conveniently, and as here shown, a number, as a pair 5 and 5a, of the quadrants may be supplied from a single main supply pipe, and similarly a number of quadrants, as 5 and 5a, may be drained by a single outlet 60 pipe.

The containers proper for the sandwiches, as the bag 3, may be of any suitable type. The illustrated bag comprises the flexible rubber body 16 desirably provided with metal 65 binding 17, and having the closure design-

nated generally as 18. The closure is provided with a suitable number of the before mentioned hooks 14 for suspending the same from the corresponding before mentioned hooks 15 on the top 2 of the container 1. Other suitable means for suspending the bag 3 may be used, as, for example, slide members replacing the hooks 14 and slidably in slide-ways on the top 2 and replacing the hooks 15. A valve 3a for connection with a vacuum 75 pump is provided at the bottom of the bag.

The illustrated closure designated generally as 18 comprises a pair of yokes 19 and 19a to which the sides 20 and 20a of the bag 3 are attached, the sides as here illustrated being attached to the yokes at 21 and 21a by suitable fastening means as 22 and 22a, as shown in Figure 5. The yokes are hinged together at each side by a pivot bolt 23 carried by an ear 24 upon the yoke 19 and passing through the yoke 19a. For locking the yokes together, the yoke 19 carries pivoted thereto at 25 a swinging plate 26 provided with a slot 27 for the reception of a bolt-like pin 28 carried by the yoke 19a. The slot is of a contour to permit of the plate 26 to swing about the pivot 25, and the pin 28 to travel along the slot when the yoke 19a is swung about the pivot 23. To hold the yokes closed (as illustrated in Figure 5), the tightening 90 nuts 29 on the bolts 28 may be tightened. To conveniently hold the yokes open, the slot 27 may be provided with an extension 30 into which the pin 28 may pass when the yokes are fully opened.

While a container divided into compartments and provided with baffles has been shown, if desired all partitions may be omitted from the container, steam coils placed in the bottom of the container for heating the water, and convection of currents depended upon to circulate the water in the container. Furthermore, cooling tubes may be placed in the top of the container for the circulation of brine or cold water for the 100 cooling of the water after treatment.

I claim:

1. In an apparatus of the character described, in combination, a fluid container having a removable top, and means for suspending safety glass assemblies from said top to hang substantially vertically in said container.

2. In an apparatus of the character described, in combination, a fluid container having a removable top, said top being provided with means for suspending a plurality of safety glass assembly holders therefrom, and a plurality of such holders provided with supporting means cooperative with said first 110 named means.

3. In an apparatus of the character described, in combination, a fluid container having a removable top, and means for suspending safety glass assemblies from said top to 115

hang substantially vertically in said container; said container being provided with a series of baffles extending alternately from the bottom to short of the top, and from the 5 top to short of the bottom, and being also provided with means for introducing and removing pressure-temperature fluid to and from said container to circulate through the same about said baffles; and said suspending 10 means being mated with the compartments formed by said baffles to locate the suspended assemblies in said compartments.

4. In an apparatus of the character described, in combination, a fluid container 15 having a removable top, means for supporting a safety glass assembly in said container for treatment therein, such means comprising a bag-like holder for reception of the assembly, and means for suspending such 20 holder from the top of said container to hang vertically therein.

5. In an apparatus for the subjection of safety glass assemblies to heat and pressure to unit the elements thereof, in combination, 25 a pressure-temperature fluid container having a removable top and having its body provided with a series of baffles extending alternately from the bottom of the container to short of the top thereof, and from the top 30 to short of the bottom thereof, means for introducing and removing pressure-temperature fluid to and from said container to circulate through the same and about said baffles, means for supporting safety glass assemblies 35 in said container, such means comprising bag-like holders for reception of the assemblies, and means for suspending said holders from said top to hang therefrom, said suspending means being mated with the compartments 40 formed by said baffles to locate the suspended assemblies in said compartments.

6. In an apparatus of the character described, in combination, a fluid container having a removable top, a plurality of holders 45 for the reception of articles to be treated in said container, said holders having a size and contour adapting them for substantially vertical side-by-side reception in said container and for insertion and withdrawal 50 from the container by way of the top opening thereof, and means for circulating temperature-pressure fluid in vertical flow and counter flow in and out of said container and about said holders.

55 7. In an autoclave apparatus for the subjection of safety glass sandwiches, while vertically positioned, to the action of a temperature-pressure fluid; a container having a top opening for the introduction and withdrawal 60 of the sandwiches, and a removable top for said opening, said container being provided with a series of baffles extending alternating from the bottom to short of the top, and from the top to short of the bottom, 65 and being also provided with means for in-

troducing and removing pressure-temperature fluid to and from said container to circulate in vertical flow and counter flow through the same and about said baffles and the received sandwiches.

In testimony whereof, I affix my signature.
JAMES H. SHERTS.
